AUTOMATIC TRAIN CONTROL SYSTEM

Alfred Ernest Hudd, London, England

Application March 6, 1934, Serial No. 714,259
In Great Britain August 16, 1932

24 Claims. (Cl. 246—63)

This invention consists in improvements in or relating to automatic train control systems and to mechanisms constituting parts thereof.

Automatic train control systems are already known in which a permanent magnet located on the train track is utilized to actuate a receiver carried on the train, whereby a warning device is energized and brakes are automatically applied when the train approaches or is passing a signal set to other than a clear position.

The track magnets are usually arranged to extend across the track and each pole is arranged to energize one only of a pair of collecting plates of a receiver on the train. This arrangement has necessitated employing a number of magnets arranged side by side in order to ensure the requisite time of operation of the receiver carried by the train as it traverses the magnets. It has been proposed to provide an upright horseshoe permanent magnet on the track arranged with its poles in the longitudinal direction of the track. Both of the poles were arranged to operate directly upon a single armature which was mounted in a swinging manner on the train. The movement of the armature was arranged to actuate a signal device and the brake mechanism. The magnet was rendered inoperative by energizing certain windings carried by the limbs thereof.

It has also been proposed to provide two sets of receivers on the train, one of which is energized by permanent magnets arranged with their poles longitudinal along the track and the other receiver being energized by electro-magnets arranged with their poles at right angles to those of the permanent magnets. In such an arrangement, when both receivers were energized simultaneously, the relay remained inoperative.

According to this invention, an automatic train control system comprises one or more permanent magnets (e. g. bar magnets) arranged on the train track with their north and south poles in the longitudinal direction of the track, electro-magnet or mechanically operated shrouding means associated with said permanent magnets and arranged to render said magnets inoperative when the track is clear, a receiver on the train embodying a relay comprising two fixed collecting plates spaced apart in the longitudinal direction of the track so as to be successively energized by both pole pieces of each magnet and having pole pieces spaced apart to provide a flux leakage path, an armature arranged to bridge said pole pieces, and mechanism operated by the movement of said armature to control said warning device and/or said train brakes.

The shrouding of the permanent magnet may be effected by one or more electro-magnets arranged with a pole, or poles, spaced a short distance from said permanent magnets. The energization of the shrouding means is controlled through a track circuit similar to those commonly used by or in conjunction with signal systems, all of which is well known and understood by those skilled in the art or it may be effected by manually controlled circuits.

A further feature of the invention consists in that at each operating location on the track, there is disposed one or more permanent magnets on one side of the centre line of the track and one or more permanent magnets arranged on the other side of the centre line and in that two magnetically operated relays are provided on said train on opposite sides of said centre line. Preferably, said relays are so operatively connected to the brake mechanism that if one relay only is energized, the brake mechanism is partly applied, while if both relays are energized either simultaneously at one operating location, or in succession after passing two operating locations, the brake mechanism is fully applied. The warning device is arranged to be sounded when a relay is first energized.

A further feature of the invention consists in that the relay comprises a movable loaded member (e. g. spring or gravity loaded) for operating a warning device and/or brake mechanism, a detent for holding said movable member in an energized position, and a movable armature operated by the aforesaid track magnet to release said detent, and means for resetting said member to its energized position. In an arrangement in which the train brakes are operated pneumatically, said movable loaded member is arranged to operate an air control valve.

In one constructional form of the relay mechanism the said movable loaded member is formed in two relatively movable parts between which is disposed a compression spring for effecting the loading, one of which parts is engageable by said detent and the other of which controls (e. g. by the valve referred to above) the warning device and brake mechanism and wherein the resetting means is so arranged that it requires to be given a reciprocating movement, the movement in one direction being arranged to move the first said part again into engagement with the detent but which locks the other part, while the return movement moves the second part into a position for releasing the brakes and stopping the warning device.

The following is a description of a train control system according to this invention, reference being made to the accompanying drawings, in which—

5 Figure 1 is a diagrammatic view of the general arrangement of the various parts of the system;

10 Figure 2 is a part side elevation and part section of a mounting for a track permanent magnet and electro-magnets for controlling the leakage flux of the permanent magnets;

15 Figure 3 is a section on the line 3—3 of Figure 2;

Figure 4 is a plan view of the arrangement shown in Figure 2;

15 Figure 5 is a part side elevation and part section of the relay mechanism carried by the train;

Figure 6 is a section on the line 6—6 of Figure 5;

20 Figure 7 is a plan view of the construction shown in Figure 6.

Referring to Figure 1, at each operating location on the track, there are mounted two permanent magnets 10, one on each side of the centre line of the track. The magnets are mounted 25 on suitable supports 11 which are better seen in Figures 2 to 4. The upper faces of the magnets are arranged to lie at a level of about one inch above the tops of the rails 12 and the poles of the magnets are arranged in the longitudinal direction of the track. Shrouding means, not shown in Figure 1 but shown in Figures 2 to 4, are mounted on the magnet support for controlling the leakage flux of the permanent magnet. When the track is clear, the shrouding means are 30 arranged to greatly minimize or eliminate the leakage flux. Mounted on the train are two magnetic relay devices 13 one on either side of the centre line of the train, only one of which is shown in Figure 1. Each relay device is controlled by two collecting plates 34, which are so disposed on the train as to be traversed across the top face of a magnet from which it is spaced about four inches. The relay device is arranged to operate a warning whistle 15 and a valve which 35 controls the flow of air through a pipe line 16 to the brake mechanism. Hand control mechanism 17 is provided for resetting the relay after it has been energized by the track mechanism, and for releasing the brakes which have been 40 applied.

Turning to Figures 2 to 4, the shrouding means comprise two electro-magnets 18, the iron cores 19 of which have secured to them cradles 20 for supporting the permanent magnets 10. The electro-magnets are so wound, that when energized, their polarities are opposite to the poles of the permanent magnets which they support. The cradles 20 are channel-shaped in section, as shown in Figure 3 and extend on either side of the permanent magnets up to the level of the top face of the magnets. The cradles are formed from soft iron and are provided with non-magnetic spacing members 21 so that the poles of the permanent magnets are separated from the cradles and poles of the electro-magnets. The electro-magnets are carried on soft iron yoke pieces 22 which are secured to a base member 23 of non-magnetic cast iron, the permanent magnets and the spacing members are retained within the cradle 20, and the cradle is secured in contact with the top of the electro-magnets by non-magnetic bolts 24 which extend through holes in the yoke-pieces 22 and are provided with nuts 24 at one end and wedge-shaped heads 25 at the other end. With this construction, pro-

vided the solenoids are not energized, it is found that the permanent magnets can be designed to afford a leakage flux which will energize the relay as it passes over them. The path of this flux can, however, be controlled, and the leakage flux adequately reduced by energizing the solenoids so that insufficient leakage flux is afforded for energizing the relays.

10 In the construction described above, the permanent magnet is formed from an alloy of chromium steel and cobalt the latter being present in the proportion of 10 per cent. Convenient dimensions of the magnet are found to be twenty-four inches in length by 4½ inches broad by 1 15 inches thick.

15 Turning now to the construction shown in Figures 5 to 7; there is shown a relay mechanism for controlling vacuum operated brakes. The train relay comprises two collector plates 34 of soft iron, which are arranged end to end lengthwise of the train and to one side of the centre line thereof. These collector plates are formed with upturned portions or brackets 35 (see Figure 6) which are provided with laterally facing pole pieces 36.

20 A soft iron armature 37 is arranged in front of the pole pieces and is secured by a spring blade 38 of phosphor bronze to a bracket 39 formed from non-magnetizable material, to which brackets the collector plates are also connected. The armature is arranged to extend downwardly beneath the pole pieces and is provided with an outwardly turned lug 40 at its lower extremity. The lug is arranged to extend between the arms of two detent levers 41. 25 The detent levers are mounted on horizontally disposed pivot pins 42 and are provided at their ends above the pivot pins with anti-friction rollers 43, while their lower extremities engage the aforesaid lugs 40.

30 The upper part of the bracket 39 is formed with a valve cavity 44 and a valve guide 45. A plate valve 46 having a hollow stem 47 is mounted in said valve guide and is arranged to engage a valve seat 48 disposed above it, which valve 45 seat is at the mouth of a part communicating with a warning whistle. The valve cavity below the valve communicates with a vacuum pipe 49 of the train brake mechanism. Within the hollow stem of the valve is slidably mounted a vertically disposed rod 50 which is hollow at its 35 upper part and is provided on its lower part with a shoulder 51, and a shank 52 which extends between the aforesaid rollers 43. Within the hollow valve stem and hollow part of the member 50 is located a compression spring 53. When the relay is set so that the train brakes are inoperative, the rollers 43 are retained in engagement with the shoulder 51 by reason of the fact that their lower extremities are held apart by the 40 lugs 40 of the armature. The spring 53 forces the valve 46 against its seating 48. As soon as the armature is energized by a permanent magnet on the track, the lugs 40 will be swung laterally out of contact with the detent levers, 45 whereupon the spring 53 will force the shoulder 51 between the rollers 43 allowing the member 50 to drop to release the valve 46, whereupon the vacuum in the brake pipe line will be broken by air entering through the warning whistle.

50 The mechanism for resetting the detent device and the valve comprises a vertically movable rod 54 mounted in bearings 55 in the bracket member 39. The upper end of the rod is connected by a steel cable 56 to a hand control (not shown). 55

The lower end of the rod has secured to it a laterally extending abutment 67, the end of which is arranged beneath the shank 52 of the member 50. A helical spring 57 surrounds the rod 54 and engages at one end with the abutment 67 and at the other end with a stop member 58 on the bracket 39. Normally the abutment 67 is retained out of engagement with the end of the shank member. A small bell crank lever 59 is mounted on said bracket member, one end of which is arranged to engage the hollow valve stem 47 and the other end of which may be brought into engagement with the groove 69 formed near the upper end of the rod 54. Thus, when the member 50 has been released by the detent levers, it may be reset by moving the abutment 67 upwardly against the action of the spring, whereby it is brought into contact with the shank 52 and forces the shoulder 51 above the rollers 43. The lower extremities of the detent levers are then separated by a spring 61, permitting the lug 40 to spring back between them. Although this operation compresses the spring 53 within the valve stem, the valve cannot move, since the end of the bell crank lever 59 is locked by being in contact with the main cylindrical surface of the vertical rod 54. As soon as the rod is lowered, however, the end of the arm 59 can enter into the channel 60 whereupon the valve is permitted to be moved upwardly into contact with its seat by said spring. The warning whistle then ceases and the brakes are released.

As already indicated above, the relay mechanism on the train may be duplicated in which case the two valves are arranged in parallel passages which both communicate with the main pipe line of the train. The size of the valves and valve parts are so selected that when one is open the air flowing therethrough is only sufficient to apply the brakes partially while when both valves are open the flow of air is sufficient to apply the brakes fully.

As indicated above, the warning whistle may be operated by the same air supply that operates the brakes; if need be, however, the whistle can be operated by steam which is controlled by a separate valve operated by the said loaded member.

It will be appreciated that the apparatus may equally well be applied to the Westinghouse pressure brake system.

I claim—

1. An automatic train control system comprising permanent magnets arranged on the railway track with their north and south poles in the longitudinal direction of the track, means adapted to render said permanent magnets inoperative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, a movable loaded member, a detent for holding said movable loaded member in an energized position, which detent is adapted to be released by said armature and signalling means connected to said movable loaded member.

2. An automatic train control system comprising permanent magnets arranged on the railway track with their north and south poles in the longitudinal direction of the track, means adapted to render said permanent magnets in-

operative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, a movable loaded member, a detent for holding said movable loaded member in an energized position, which detent is adapted to be released by said armature and signalling and brake controlling means connected to the said movable loaded member.

3. An automatic train control system comprising permanent magnets arranged on the railway track with their north and south poles in the longitudinal direction of the track, means adapted to render said permanent magnets inoperative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, a movable loaded member, a detent for holding said movable loaded member in an energized position, which detent is adapted to be released by said armature, signalling and brake controlling means connected to the said movable loaded member and hand-operated means for re-energizing said loaded member and effecting the re-engagement of said detent therewith.

4. An automatic train control system comprising permanent magnets arranged on the railway track with their north and south poles in the longitudinal direction of the track, means adapted to render said permanent magnets inoperative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, a movable loaded member, a detent for holding said movable loaded member in an energized position, which detent is adapted to be released by said armature, pneumatic signalling and brake controlling mechanism, a valve for controlling said mechanism, which valve is connected to said movable loaded member.

5. An automatic train control system comprising permanent magnets arranged on the railway track with their north and south poles in the longitudinal direction of the track, means adapted to render said permanent magnets inoperative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, two relatively movable members, signalling and brake controlling means connected to the first of said movable members, a compression spring disposed between said movable members, a detent for holding the second of said members in a position to energize said spring and force the first movable member into an inoperative position, which armature is adapted to release said detent whereby said signalling and brake controlling means are rendered operative.

6. An automatic train control system comprising

- ing permanent magnets arranged on the railway track with their north and south poles in the longitudinal direction of the track, means adapted to render said permanent magnets inoperative when the track is clear, two fixed magnetic-flux collecting plates on the train spaced apart in the longitudinal direction of the track and so positioned as to be successively energized by both poles of one of said permanent magnets when the train is in movement, a movable armature associated with said collecting plates, two relatively movable members, signalling and brake controlling means connected to one of said movable members, a compression spring disposed between 10 said movable members, a detent for holding one of said members in a position to energize said spring and force the other member into an inoperative position, which armature is adapted to release said detent whereby said signalling and 15 brake controlling means are rendered operative, and reciprocable re-setting means adapted to engage both said members so that the movement of the re-setting means in one direction re-engages one member with the detent but locks the other member in the position in which the signalling and brake mechanism are operative, while return movement of said re-setting means moves said latter member to render the signalling and 20 brake mechanism inoperative.

7. An automatic train control system comprising permanent magnets arranged on the railway track with their north and south poles in the longitudinal direction of the track, electro-magnetic means adapted to render said permanent magnet inoperative when the track is clear, two fixed magnetic-flux collecting plates on the train spaced apart in the longitudinal direction of the track and so positioned as to be successively energized by both poles of the permanent magnets when the train is in movement, pole pieces fixed to said collecting plates to provide a flux leakage between them, each of which pole pieces is provided with a face lying in an upright plane extending along the track, an armature mounted to move towards and away from said pole pieces across the track, a movable loaded member, a detent for holding said movable loaded member in an energized position which detent is adapted to be released by said armature, and signalling and 25 brake controlling means connected to said movable loaded member.

8. An automatic train control system comprising permanent magnets arranged on the railroad track with their north and south poles in the longitudinal direction of the track, electromagnets arranged with their poles opposite the poles of the permanent magnets, means for energizing said electromagnets to be of opposite polarity to the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signalling means on the train adapted to be controlled by said armature.

9. An automatic train control system comprising permanent magnets arranged on the railroad track with their north and south poles in the longitudinal direction of the track, electromagnets arranged with their poles opposite the poles of the permanent magnets, means for energizing said electromagnets to be of opposite polarity to the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signalling means on the train adapted to be controlled by said armature.

10. An automatic train control system comprising permanent magnets arranged on the railroad track with their north and south poles in the longitudinal direction of the track, electromagnets arranged with their poles opposite the poles of the permanent magnets, means for energizing said electromagnets to be of opposite polarity to the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and brake controlling means on the train adapted to be controlled by said armature.

11. An automatic train control system comprising permanent straight bar magnets arranged on the railroad track with their north and south poles in the longitudinal direction of the track, two electro-magnets associated with each bar magnet, one opposite each pole, means for energizing said electromagnets to be of opposite polarity to the respective poles of the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signaling means on the train adapted to be controlled by said armature.

12. An automatic train control system comprising permanent straight bar magnets arranged on the railroad track with their north and south poles in the longitudinal direction of the track, an electro-magnet associated with each pole of each of the bar magnets, a pole of each of which electro-magnets comprises a cradle for supporting the bar magnet, non-magnetic material adapted to space the bar magnet from said cradle, means for energizing said electromagnets to be of opposite polarity to the respective poles of the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signalling means on the train adapted to be controlled by said armature.

13. An automatic train control system comprising permanent magnets arranged on the railroad track with their north and south poles in the longitudinal direction of the track, electromagnets arranged with their poles opposite the poles of the permanent magnets, means for energizing said electromagnets to be of opposite polarity to the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signalling means on the train adapted to be controlled by said armature.

traversed by both poles of one of said permanent magnets and by the associated electromagnets when the train is in movement, pole pieces fixed to said collecting plates to provide a flux-leakage path, a movable armature arranged in one position to bridge said latter pole pieces, and signalling and brake controlling means on the train controlled by the movement of said armature.

14. An automatic train control system comprising permanent bar magnets arranged on both sides of an imaginary line extending along the railroad track with their poles in the longitudinal direction of the track, electromagnets arranged with their poles opposite the poles of the permanent magnets, means for energizing said electromagnets to be of opposite polarity to the permanent magnets, two pairs of magnetic-flux collecting plates on the train, one pair on each side of said imaginary line, the plates of each of said pairs being spaced apart in the longitudinal direction of the track and so positioned as to be successively traversed by both poles of one of said permanent magnets and by the associated electromagnets, an armature associated with each pair of plates, and brake controlling means on the train adapted to be controlled by both of said armatures.

15. An automatic train control system comprising at each control location on the railroad track two long bar permanent magnets, one arranged on each side of the center line of the track with their poles in the longitudinal direction of the track, electromagnets arranged with their poles opposite the poles of the permanent magnets, means for energizing said electromagnets to be of opposite polarity to the permanent magnets, two fixed magnetic-flux collecting plates on the train spaced apart in the longitudinal direction of the track and so positioned as to be successively traversed by both poles of one of said permanent magnets and by the associated electromagnets when the train is in movement, a movable armature associated with said collecting plates, and signalling means on the train adapted to be controlled by said armature.

16. An automatic train control system comprising at each control location on the railroad track two long bar magnets, one arranged on each side of the center line of the track with their poles in the longitudinal direction of the track, electromagnets arranged with their poles opposite the poles of the permanent magnets, means for energizing said electromagnets to be of opposite polarity to the permanent magnets, two pairs of magnetic-flux collecting plates on the train, one pair on each side of said imaginary line, the plates of each of which pairs are spaced apart in the longitudinal direction of the track and so positioned as to be successively traversed by both poles of one of said bar magnets and by the associated electromagnets, an armature associated with each pair of plates, and brake controlling means on the train adapted to be controlled by both of said armatures.

17. An automatic train control system comprising permanent bar magnets arranged on both sides of an imaginary line extending along the track with their poles in the longitudinal direction of the track, electromagnets arranged with their poles opposite the poles of the permanent magnets, means for energizing said electromagnets to be of opposite polarity to the permanent magnets, two pairs of magnetic-flux collecting plates on the train, one pair on each

side of said imaginary line, the plates of each of which pairs are spaced apart in the longitudinal direction of the track and so positioned as to be successively traversed by both poles of one of said bar magnets and by the associated electromagnets, an armature associated with each pair of plates, and brake control means on the train adapted to be controlled partly by either of said armatures alone or wholly by the two armatures together.

18. An automatic train control system comprising permanent bar magnets arranged on both sides of an imaginary line extending along the track with their poles in the longitudinal direction of the track, electromagnets arranged with their poles opposite the poles of the permanent magnets, means for energizing said electromagnets to be of opposite polarity to the permanent magnets, two pairs of magnetic-flux collecting plates on the train, one pair on each side of said imaginary line, the plates of each of which pairs are spaced apart in the longitudinal direction of the track and so positioned as to be successively traversed by both poles of one of said bar magnets and by the associated electromagnets, an armature associated with each pair of plates, and signalling means on the train adapted to be controlled by either of said armatures alone, and brake controlling means adapted to be controlled partly by either of said armatures alone or wholly by the two armatures together.

19. An automatic train control system comprising permanent bar magnets arranged on both sides of an imaginary line extending along the track with their poles in the longitudinal direction of the track, electromagnets arranged with their poles opposite the poles of the permanent magnets, means for energizing said electromagnets to be of opposite polarity to the permanent magnets, two pairs of magnetic-flux collecting plates on the train, one pair on each side of said imaginary line, the plates of each of which pairs are spaced apart in the longitudinal direction of the track and so positioned as to be successively traversed by both poles of one of said bar magnets and by the associated electromagnets, an armature associated with each pair of plates, and signalling and brake controlling means adapted to be controlled by both said armatures.

20. An automatic train control system comprising permanent magnets arranged on the railroad track with their north and south poles in the longitudinal direction of the track, electromagnets associated therewith, two fixed magnetic-flux collecting plates on the train spaced apart in the longitudinal direction of the track and so positioned as to successively traverse both poles of one of said permanent magnets when the train is in movement, said electromagnets having their north and south poles opposite the south and north poles respectively of the permanent magnets, whereby the juxtaposed opposite poles of said permanent magnets and said electromagnets are simultaneously traversed by one of said collecting plates, a movable armature associated with said collecting plate, and signalling means on the train controlled by said armature.

21. In an automatic train control system, permanent magnets on the railway track, means adapted to render said permanent magnets inoperative when the track is clear, magnetic-flux collecting plates on the train so positioned as to be energized by said permanent magnets when the train is in movement, a movable armature

- associated with said collecting plates, two relatively movable members mechanically loaded for movement relatively to one another, signal and brake control means connected to one of said movable members, a mechanical detent for holding said movable loaded member in an energized position, which armature is adapted to release said detent whereby said signal and brake control means are rendered inoperative.
- 10 22. In an automatic train control system, permanent magnets on the railway track, means adapted to render said permanent magnets inoperative when the track is clear, magnetic-flux collecting plates on the train so positioned as to be energized by said permanent magnets when the train is in movement, a movable armature associated with said collecting plates, two relatively movable members, signalling and brake controlling means connected to the first of said movable members, a compression spring disposed between said movable members, a detent for holding the second of said members in a position to energize said spring and force the first movable member into inoperative position, which armature is adapted to release said detent whereby said signalling and brake controlling means are rendered operative.
- 15 23. An automatic train control system comprising permanent bar magnets arranged on both sides of an imaginary line extending along the railroad track with their poles in the longitudinal direction of the track, electromagnets arranged with their poles opposite the poles of the permanent magnets, means for energizing said electro-magnets to be of opposite polarity to the permanent magnets, two pairs of magnetic-flux collecting plates on the train, one pair on each side of said imaginary line, the plates of each of said pairs being spaced apart
- 20 in the longitudinal direction of the track and so positioned as to successively traverse both poles of one of said permanent magnets and the associated electro-magnets when the train is in movement, a movable armature associated with each pair of collecting plates, signalling and brake controlling means, and means controlled by said armature for controlling said signalling and brake controlling means.
- 25 24. An automatic train control system comprising permanent bar magnets arranged on both sides of an imaginary line extending along the railroad track with their poles in the longitudinal direction of the track, electro-magnets arranged with their poles opposite the poles of the permanent magnets, means for energizing said electro-magnets to be of opposite polarity to the permanent magnets, two pairs of magnetic-flux collecting plates on the train, one pair on each side of said imaginary line, the plates of each of said pairs being spaced apart in the longitudinal direction of the track and so positioned as to successively traverse both poles of one of said permanent magnets and the associated electro-magnets when the train is in movement, a movable armature associated with each pair of collecting plates, two relatively movable members associated with each armature, signalling and brake controlling means connected to one of said movable members, a compression spring disposed between said movable members, a detent for holding one of said members in a position to energize said spring and force the other member into an inoperative position, said armature being adapted to release its associated detent whereby said signalling and brake controlling means are rendered operative.

ALFRED ERNEST HUDD.
